(57) **ABSTRACT**

An ink-jet recording apparatus has an ink passage into which a water-based ink or a preservation solution is filled. The ink passage employs a rubber member formed from a rubber in which a butyl rubber polymer serving as a base polymer, zinc oxide serving as a vulcanization agent, and a thiourea-based compound serving as a vulcanization accelerator are employed. Each of the water-based ink and the preservation solution comprises water and a water-soluble organic solvent. The ink and the preservation solution contain water in an amount of 70 wt. % to about 85 wt. % with respect to the total weight of the water-based ink and the preservation solution, respectively.

1

INK-JET RECORDING APPARATUS

BACKGROUND OF THE INVENTION

1. Field of the Invention

The present invention relates to an ink-jet recording apparatus in which insoluble materials originating from rubber members employed in an ink passage are prevented from precipitating into a water-based ink or a preservation solution filled into the ink passage.

2. Description of the Related Art

An ink-jet recording apparatus is an apparatus for performing recording by causing ink to adhere to a recording material such as recording paper by means of an ink ejection method such as a thermal method or a piezo method. In the thermal method, ink is rapidly heated to generate bubbles, and fine droplets of the ink are ejected from fine nozzles by utilizing the pressure generated by the rapid heating. In the piezo method, fine droplets of ink are ejected by use of a piezoelectric element.

In an ink-jet recording apparatus, rubber members are employed in an ink passage comprised of an ink tank, an ink-jet head and the like. These rubber members include, but are not limited to, a cap which covers nozzles of the ink-jet head, a wiper which cleans the end face of the nozzles of the ink-jet head, a seal packing which is placed at the joint portion between components, and the like. In addition, if the ink tank is provided separately from the ink-jet head, the rubber members also include a tube which supplies ink from the ink tank to the ink-jet head, and the like.

However, when the rubber members come in contact with a water-based ink (hereinafter simply referred to as an ink) employed in ink-jet recording or with a preservation solution filled into an ink passage at the time of shipping or during long-term storage, the additives contained in the rubber members are dissolved in the ink or the preservation solution. The dissolved additives then precipitate as an insoluble material, thereby causing a problem such as clogging of nozzles of an ink-jet head.

In view of the above, a method has been proposed in US-A1-2005116984. In this method, rubber materials to be employed in an ink passage are immersed in water at 60° C. for a predetermined time in a sealed container for determining the amount of dissolved materials to thereby select suitable rubber materials.

However, the amounts and kinds of the insoluble materials precipitating into an ink or a preservation solution depend on the composition of the ink or the preservation solution. Therefore, even when the rubber materials selected by means of the method of US-A1-2005116984 are employed in the rubber members forming the ink passage, the problem of the precipitation of the insoluble materials occasionally arises. Specifically, the problem may arise when the composition of the ink is adjusted such that the ink has a dynamic surface tension preferable for ejection stability and when the composition of the preservation solution is adjusted such that the preservation solution has a dynamic surface tension preferable for replaceability with the ink and wettability.

SUMMARY OF THE INVENTION

In view of such problems in conventional technology, it is an object of the invention to prevent, in an ink-jet recording apparatus, insoluble materials originating from rubber members employed in an ink passage from precipitating. More specifically, the object is to prevent the insoluble materials from precipitating when an ink is employed which has a

2

dynamic surface tension preferable for ejection stability and when a preservation solution is employed which has a dynamic surface tension preferable for wettability and replaceability with ink.

5 The present inventors have formed rubber members employed in an ink passage of an ink-jet recording apparatus from a rubber in which a butyl rubber polymer serving as a base rubber polymer, zinc oxide serving as a vulcanization agent and a thiourea-based compound (hereinafter referred to 10 as a thiourea-based vulcanization accelerator) serving as a vulcanization accelerator are employed. In addition, the inventors have employed an ink and a preservation solution each of which contains water in a specific ratio. Consequently, the inventors have found that each of the ink and the 15 preservation solution has a dynamic surface tension at which excellent ejection stability or excellent wettability is obtained. The inventors have also found that, even when the thiourea-based vulcanization accelerator is dissolved in the ink or the preservation solution from the rubber members, the 20 precipitation thereof as an insoluble material can be prevented since the dissolved thiourea-based vulcanization accelerator remains stable.

Accordingly, the present invention provides an ink-jet recording apparatus in which a water-based ink or a preservation 25 solution is filled into an ink passage. In the ink-jet recording apparatus, a rubber member employed in the ink passage is formed from a rubber in which a butyl rubber polymer serving as a base polymer, zinc oxide serving as a vulcanization agent and a thiourea-based compound serving 30 as a vulcanization accelerator are employed. In addition, the water-based ink comprises at least a coloring agent, water and a water-soluble organic solvent, the amount of water being about 70 wt. % to about 85 wt. % with respect to the total weight of the water-based ink. Furthermore, the preservation 35 solution comprises at least water and a water-soluble organic solvent, the amount of water being about 70 wt. % to about 85 wt. % with respect to the total weight of the preservation solution.

In the ink-jet recording apparatus of the present invention, 40 the rubber member employed in the ink passage is formed from a rubber obtained by vulcanizing a butyl rubber polymer with zinc oxide and a thiourea-based vulcanization accelerator. In addition, each of the ink and the preservation solution employed in the ink-jet recording apparatus comprises water 45 in a specific ratio. Therefore, even if the thiourea-based vulcanization accelerator is dissolved in the ink or the preservation solution from the rubber member, the dissolved state thereof remains stable. Hence, insoluble materials originating 50 from the rubber are prevented from precipitating in the ink or the preservation solution filled into the ink passage.

In addition, since the ink comprises water in a specific ratio, the ink has excellent ejection stability. Furthermore, since the preservation solution comprises water in a specific ratio, the rubber members does not swell and the preservation 55 solution has excellent wettability in the ink passage and excellent replaceability with the ink.

DETAILED DESCRIPTION OF THE PREFERRED EMBODIMENTS

60 The present invention will next be described in detail. The ink-jet recording apparatus of the present invention is characterized in that rubber members employed in part of an ink passage are formed from a rubber in which a butyl rubber polymer serving as a base polymer, zinc oxide serving as a vulcanization agent and a thiourea-based compound serving 65 as a vulcanization accelerator are employed. The apparatus is

also characterized in that each of an ink and a preservation solution employed in the apparatus comprises water in a specific ratio. The configuration of the ink-jet recording apparatus other than the above features may be the same as that of a known ink-jet recording apparatus. No limitation is imposed on an ink ejection method, and a thermal method a piezo method, or any other method may be employed.

In the ink-jet recording apparatus, the rubber members employed in a part of the ink passage include, but are not limited to, a cap which covers nozzles of an ink-jet head, a wiper which cleans the end face of the nozzles of the ink-jet head, and the like. In addition, if an ink tank is provided separately from the ink-jet head, the rubber members also include a tube which supplies ink from the ink tank to the ink-jet head. Further, the rubber members also include a seal packing which is an elastic member held between a buffer tank and a head unit, as disclosed in Japanese Patent Application No. 2004-207208.

As a base polymer of the rubber forming the rubber members, a butyl rubber polymer is employed since it has low gas permeability and is suitable for a seal packing or the like preventing drying in an ink tank. The butyl rubber polymer refers to an uncrosslinked isoprene-isobutylene rubber polymer obtained by copolymerizing isoprene and isobutylene and also refers to a compound obtained by substituting a part thereof with a halogen. Specifically, a commercial product such as HT-1066 or HT-1068 (products of JSR Corporation) may be employed.

As the vulcanization agent, zinc oxide is employed due to its high vulcanization rate. The mixing amount of zinc oxide is preferably about 2.5 parts by weight to about 7.5 parts by weight per 100 parts by weight of the base polymer of the rubber forming the rubber members. When the mixing amount of zinc oxide is too low, the rubber members are likely to swell by the ink or the preservation solution due to insufficient vulcanization. When the mixing amount is too high, insoluble materials are prone to precipitate in the ink or the preservation solution.

As the vulcanization accelerator, a thiourea-based compound is employed. The thiourea-based compound has solubility in water. Thus, when the ink and the preservation solution comprises water, the precipitation of the thiourea-based compound can be prevented in the ink and the preservation solution even when the compound is dissolved in the ink and the preservation solution from the rubber members. Since vulcanization accelerators other than the thiourea-based compound are not easily dissolved in water, such effects cannot be obtained.

As the thiourea-based compound, for example, a compound represented by the following formula (1) can be employed:

(1)

wherein R1, R2, R3 and R4 are independently H, an alkyl group having 1 to 12 carbon atoms,

5

group or

10

group, and R2 and R3 may be joined to form an alkylene group. However, the larger the molecular weight of the thiourea-based compound, the lower the solubility in water. Thus, a thiourea-based compound having a molecular weight of about 200 or less is preferable.

Specific examples of the preferred thiourea-based compound include, but are not limited to, ethylene thiourea (M. W.=102) represented by the following formula (1a):

(1a)

trimethylthiourea (M. W.=118) represented by the following formula (1b):

(1b)

N,N-diethylthiourea (M. W.=132) represented by the following formula (1c):

(1c)

di(O-tolyl) thiourea (M. W.=256) represented by the following formula (1d):

(1d)

5

N,N'-dibutylthiourea (M. W.=188) represented by the following formula (1e):

diphenylthiourea (M. W.=228) represented by the following formula (1f):

dilaurylthiourea (M. W.=282) represented by the following formula (1g):

and the like.

Of these, N,N-diethylthiourea represented by formula (1c) is preferable due to its particularly high solubility in water.

The preferred mixing amount of the thiourea-based compound is determined such that the appropriate vulcanization rate is obtained. That is, the mixing amount is preferably about 1 part by weight to about 3 parts by weight per 100 parts by weight of the base polymer of the rubber. When the mixing amount of the thiourea-based compound is too low, a longer vulcanization molding time is required, causing a decrease in production efficiency. When the mixing amount is too high, the dissolved amount in the ink or the preservation solution becomes large. Thus, disadvantageously, the precipitation of the compound is more likely to occur in the ink or the preservation solution.

Various additives may be added to the rubber composition in accordance with need. Examples of such additives include, but are not limited to: lubricants such as calcium stearate, stearic acid amide and magnesium oxide; fillers such as carbon black, calcium carbonate and silicon dioxide and the like; softening agents such as paraffin oil and the like; antioxidants; scorch retarders; and the like.

In a method of manufacturing the rubber members from the above rubber composition, kneading is performed by means of a kneading apparatus such as a Banbury mixer, a kneader or a twin roll mill. Further, heating is carried out normally at about 140° C. to about 200° C. for about 5 minutes to about 15 minutes in a vulcanization step for the rubber.

An ink which comes in contact with the above-mentioned rubber members in the ink passage in the ink-jet recording apparatus comprises at least a coloring agent, water and a water-soluble organic solvent.

In addition, the ink preferably has a dynamic surface tension at a lifetime of 100 ms of about 35 mN/m to about 45

6

mN/m as determined by a maximum bubble pressure method at a measurement temperature of 25° C. By setting the dynamic surface tension at a lifetime of 100 ms as determined by the maximum bubble pressure method at a measurement temperature of 25° C. to about 35 mN/m to about 45 mN/m, ejection stability from an ink-jet head can be imparted to the ink. If the dynamic surface tension is less than about 35 mN/m, a desirable meniscus is not formed at a nozzle of an ink-jet head, thereby causing difficulty in ejecting the ink as fine droplets. Moreover, the wettability of the ink to a recording material such as paper becomes excessively high, causing deterioration of print quality. On the contrary, if the dynamic surface tension exceeds about 45 mN/m, difficulty arises in introducing the ink into an ink-jet head, thereby causing a problem that the ink is not ejected.

It has been known that the dynamic surface tension is generally determined by an oscillating jet method, a meniscus method, the maximum bubble pressure method or other method. However, the value of the dynamic surface tension defined in the present invention is determined by means of the maximum bubble pressure method.

In the determination of the dynamic surface tension by means of the maximum bubble pressure method, a gas is fed from a gas supply source to a probe to generate a bubble at the end of the probe which is immersed in an ink. At this time, the generation rate of the bubble is changed by changing the flow rate of the gas. The pressure on the bubble from the ink is changed along with the bubble generation rate change, and the surface tension is determined through this pressure. The pressure reaches the maximum (the maximum bubble pressure) when the radius of the bubble becomes equal to the radius of the end portion of the probe. Thus, the dynamic surface tension σ of the ink at this moment is represented by the following equation:

$$\sigma = (\Delta P \cdot r) / 2$$

wherein r is the radius of the end portion of the probe, and ΔP is the difference between the maximum pressure and the minimum pressure on the bubble.

The term "lifetime" refers to a period of time from when a bubble is separated from the probe after the pressure reaches the maximum bubble pressure to form a new surface to when the pressure again reaches the maximum bubble pressure.

In order to prevent clogging of a nozzle, an ink filter and the like caused by impurities contained in water, the water employed in the ink is not ordinary tap water but preferably high purity water such as ion-exchanged water, distilled water or ultrapure water. In the ink, the water is capable of dissolving the thiourea-based vulcanization accelerator and prevents the precipitation thereof. The amount of water with respect to the total ink weight is about 70 wt. % to about 85 wt. %. When the amount of water is less than about 70 wt. %, the precipitation of the thiourea-based vulcanization accelerator dissolved in the ink cannot be reliably prevented. When the amount of water exceeds about 85 wt. %, the dynamic surface tension of the ink becomes excessively high, causing difficulty in introducing the ink into an ink-jet head.

Preferably, the mixing composition of the water-soluble organic comprised of in the ink is adjusted such that the dynamic surface tension falls within the above range. Specifically, a glycol ether is preferably employed as the water-soluble organic solvent. A glycol ether reduces the dynamic surface tension, moderately enhances the penetration rate of ink into a recording material such as paper, and improves the drying characteristics.

Specific examples of the glycol ether include, but are not limited to, diethylene glycol methyl ether, diethylene glycol butyl ether, diethylene glycol isobutyl ether, dipropylene glycol methyl ether, dipropylene glycol propyl ether, dipropylene glycol isopropyl ether, dipropylene glycol butyl ether, triethylene glycol methyl ether, triethylene glycol butyl ether, tripropylene glycol methyl ether, tripropylene glycol butyl ether and the like. Of these, triethylene glycol butyl ether, dipropylene glycol propyl ether and the like are preferable since they are excellent in the capability of adjusting the dynamic surface tension and in print quality. These may be employed alone or as a mixture of two or more.

The amount of the glycol ether with respect to the total weight of the ink is preferably about 0.1 wt. % to about 10 wt. %, and more preferably about 3 wt. % to about 7 wt. %. Disadvantageously, if the amount of the glycol ether is too low, the dynamic surface tension becomes excessively high, and thus difficulty arises in introducing the ink into an ink-jet head. In addition, the penetration rate of the ink into a recording material is lowered, thereby causing problems in drying time and bleeding. Further, disadvantageously, if the amount of the glycol ether is too high, the dynamic surface tension becomes excessively low. Thus, a desirable meniscus cannot be formed at a nozzle of an ink-jet head, and swelling occurs in the rubber members. In addition, since the ink excessively penetrates into a recording material, the ink reaches the back surface of the recording material, and blurring occurs considerably.

As the water-soluble organic solvent, a humectant for preventing drying of the ink at a nozzle and for improving the solution stability of the ink may be optionally added in addition to the glycol ether. Specific examples of the humectant include, but are not limited to: polyhydric alcohols such as ethylene glycol, propylene glycol, diethylene glycol, triethylene glycol, dipropylene glycol, polyethylene glycol, polypropylene glycol, 1,3-butanediol, 1,5-pentandiol, 1,6-hexanediol, glycerin, 1,2,6-hexanetriol, 1,2,4-butanetriol, 1,2,3-butanetriol and the like; nitrogen-containing heterocyclic compounds such as N-methyl-2-pyrrolidone, N-hydroxyethyl-2-pyrrolidone, 2-pyrrolidone, 1,3-dimethylimidazolidinone, ϵ -caprolactam and the like; amides such as formamide, N-methylformamide, N,N-dimethylformamide and the like; amines such as ethanolamine, diethanolamine, triethanolamine, ethylamine, diethylamine, triethylamine and the like; sulfur-containing compounds such as dimethyl sulfoxide, sulfolane, thioldiethanol and the like; and the like. These may be employed alone or as a mixture of two or more.

The amount of the humectant depends on the composition of the ink and the desired characteristics of the ink and is determined over a wide range. Normally, the amount of the humectant with respect to the total weight of each ink is preferably about 0 wt. % to about 40 wt. %, and more preferably about 0 wt. % to about 30 wt. %. The amount exceeding about 40 wt. % is not preferable since the viscosity of the ink unnecessarily increases to potentially cause problems such as difficulty in ejecting the ink from a nozzle of an ink-jet head and significant retardation of drying on a recording material.

Further, a monohydric alcohol such as ethanol or isopropyl alcohol may be employed for the purpose of controlling the penetrability of the ink into a recording material and the drying characteristics of the ink.

As the coloring agent, water-soluble dyes typified by direct dyes, acid dyes, basic dyes, reactive dyes, and the like may be employed, and various inorganic pigments and organic pigments may also be employed. In addition, a self-dispersing type pigment may be employed which is obtained by subjecting a pigment to a surface treatment.

The ink employed in the ink-jet recording apparatus of the present invention comprises generally employed additives such as a dispersing agent, a viscosity modifier, a surfactant, a pH modifier and a preservative-mildewproofing agent in accordance with need. Among them, for achieving excellent print quality and for ease of introducing the ink, a polyoxyethylene alkyl ether sulfate-based surfactant represented by the following formula is preferably employed:

wherein R is an alkyl group having 12 to 15 carbon atoms, n is 2 to 4, and M is Na or triethanolamine. Examples of the surfactant which is commercially available include, but are not limited to: SUNNOL (a registered trademark) NL-1430, LMT-1430 and DM-1470 (products of LION Corporation); EMAL (a registered trademark) 20C, 20CM and 20T (products of Kao Corporation); SANDET (a registered trademark) EN, ET and END (products of Sanyo Chemical Industries, Ltd.); and the like.

Moreover, if the ink is applied to an ink-jet printer of a thermal type utilizing the action of thermal energy to eject the ink, an additive for adjusting thermal physical properties such as specific heat, thermal expansion coefficient and thermal conductivity may be employed.

In a conventional ink-jet recording apparatus, the ink having a dynamic surface tension of about 35 mN/m to about 45 mN/m adjusted by use of the above-mentioned components causes the precipitation of insoluble materials originating from the vulcanization accelerator into the ink. This results in that an ink filter is clogged and the ink is not ejected from a nozzle of an ink-jet head. However, in the ink-jet recording apparatus of the present invention, such problems are solved.

The preservation solution employed in the ink-jet recording apparatus of the present invention is prepared from the water and the water-soluble organic solvents such as the glycol ether, which are the same as those in the above-mentioned ink. However, the coloring agent may be omitted. Here, preferably, the dynamic surface tension at a lifetime of 100 ms as determined by the maximum bubble pressure method at a measurement temperature of 25° C. is adjusted to about 30 mN/m to about 35 mN/m. If this dynamic surface tension is less than about 30 mN/m, the wettability of the preservation solution to the rubber members becomes excessively high, and the penetrability also becomes excessively high, thereby causing a problem of swelling of the rubber members. On the contrary, if the dynamic surface tension exceeds about 35 mN/m, the preservation solution cannot be smoothly replaced with ink at the time of initial introduction of the ink into an ink-jet head.

In order for the preservation solution to sufficiently dissolve the thiourea-based vulcanization accelerator as well as to have such a dynamic surface tension, the amount of water with respect to the total weight of the preservation solution is preferably about 70 wt. % to about 85 wt. %.

Moreover, for ease of introducing the ink, an acetylene glycol-based surfactant represented by the following formula is preferably added:

wherein the sum of m and n is 0 to 50, and R1, R2, R3 and R4 are independently an alkyl group.

Examples of the surfactant which is commercially available include, but are not limited to, OLFINE (a registered trademark) E1010 and E1004, SURFYNOL (a registered trademark) 104E (products of Nissin Chemical Industry Co., Ltd.) and the like.

EXAMPLES

The present invention will next be specifically described by way of examples.

(1) Preparation of Inks and Preservation Solutions

The compositions shown in Table 1 were employed for the inks and the preservation solutions, and all the components were stirred and mixed to obtain inks 1 to 4 and preservation solutions 1 to 4. In the ink compositions shown in Table 1, the actual mixing amount of each of the components is listed in weight percent (wt. %).

(2) Preparation of Rubber Sheets

According to each of the rubber composition shown in Table 2, the components were successively fed to a rubber mixer, were kneaded, and were then discharged therefrom. The discharged mixture was extruded into a sheet-like shape by means of a biaxial extruder and then was subjected to vulcanization molding (at 165° C. for 7 minutes) to thereby obtain rubber sheets 1 to 5 for evaluation.

(3) Evaluation of Precipitation of Rubber (Precipitation Evaporation)

Each of the rubber sheets prepared in (2) was cut to dimensions of 50 mm length, 10 mm width and 2 mm thickness to form a sample for evaluation.

According to the combinations of experimental examples A-1 to A-20 and B-1 to B-20 shown in Tables 3 and 4, each of the above-mentioned samples was immersed into 10 mL of the ink or the preservation solution in a sealed container and was left to stand for two weeks in a thermostatic bath at 60° C. Thereafter, the immersed sample was removed. For each case, the ink or the preservation solution after the removal of the immersed sample was filtrated with an electroformed filter (a pore size of 13 µm and an effective filtration area of 8 cm²) to measure the time required for the filtration. In addition, as a control, the inks and the preservation solutions to which the sample was not added were left to stand under the same conditions as above (at 60° C. for two weeks) and were filtrated with an electroformed filter having the same specification as above to determine the time required for the filtration (the reference time). For each of the inks and each of the preservation solutions into which the sample was immersed, the ratio of the time required for the filtration to the reference time was determined and evaluated by the following criteria.

20 The results are shown in Tables 3 and 4.

AA: the required filtration time is less than 130% of the reference time.

A: the required filtration time is at least 130% and less than 200% of the reference time.

25 B: the required filtration time is at least 200% and less than 400% of the reference time.

C: the required filtration time is at least 400% of the reference time.

The electroformed filters after the filtration were observed 30 under a microscope, and it was found that the larger the ratio of the above-mentioned filtration time to the reference time, the more the amount of the precipitates.

(4) Evaluation of Evaporation Characteristics (Evaporation Characteristic Evaluation)

Each of the inks and the preservation solutions was left to stand in a thermostatic bath at 60° C. until the weight remained unchanged. Subsequently, the presence or absence of precipitates and the presence or absence of the solids of the ink or the preservation solution were observed under a microscope, and the evaluation was made by the following criteria. The results are shown in Tables 3 and 4.

40 A: Precipitates and the solids of the ink or the preservation solution were not found by microscope observation.

B: Precipitates or the solids of the ink or the preservation solution were found by microscope observation.

As can be seen from the results in Tables 3 and 4, for the rubber sample 4 in which a thiuram-based vulcanization accelerator was employed and for the rubber sample 5 in which a dithiocarbamate-based vulcanization accelerator was employed, the precipitation evaluation results were unfavorable in all the inks and preservation solutions. On the other hand, for the rubber samples 1 to 3 in which the thiourea-based vulcanization accelerator was employed, the precipitation evaluation results were excellent in the inks 1 to 3 and the preservation solutions 1 to 3. However, since the ink 4 and the preservation solution 4 comprises a smaller amount of water, insoluble materials precipitated from the rubber samples 1 to 3.

Further, since the ink 1 and the preservation solution 1 comprises a larger amount of water, the evaporation characteristics evaluation results were unfavorable.

The present invention is useful as an inkjet recording apparatus which does not suffer performance deterioration due to precipitates with an ink or a preservation solution filled therein.

The entire disclosure of the specification, claims and summary of Japanese Patent Application No. 2005-233675 filed on Aug. 11, 2005 is hereby incorporated by reference.

13

What is claimed is:

- An ink-jet recording apparatus comprising:
an ink passage through which at least one of a water-based ink and a preservation solution flows; and
a rubber member in the ink passage, said rubber member being formed from a rubber in which a butyl rubber polymer serving as a base polymer, zinc oxide serving as a vulcanization agent, and a thiourea-based compound serving as a vulcanization accelerator are employed wherein the thiourea-based compound is ethylene thiourea, diphenylthiourea, or dilaurylthiourea,
wherein the water-based ink includes at least a coloring agent, water and a water-soluble organic solvent, an amount of water being about 70 wt. % to about 85 wt. % with respect to the total weight of the water-based ink,
and
wherein the preservation solution includes at least water and a water-soluble organic solvent, an amount of water being about 70 wt. % to about 85 wt. % with respect to the total weight of the preservation solution.

2. The ink-jet recording apparatus according to claim 1, wherein

the thiourea-based compound has a molecular weight of about 200 or less.

3. The ink-jet recording apparatus according to claim 1, wherein

the water-based ink has a dynamic surface tension at a lifetime of 100 ms of about 35 mN/m to about 45 mN/m as determined by a maximum bubble pressure method at a measurement temperature of 25° C.

4. The ink-jet recording apparatus according to claim 1, wherein

the water-based ink further comprises a polyoxyethylene alkyl ether sulfate-based surfactant represented by the following formula:

wherein R is an alkyl group having 12 to 15 carbon atoms, M is Na or triethanolamine, and n is 2 to 4.

14

- The ink-jet recording apparatus according to claim 1, wherein

the preservation solution has a dynamic surface tension at a lifetime of 100 ms of about 30 mN/m to about 35 mN/m as determined by a maximum bubble pressure method at a measurement temperature of 25° C.

- The ink-jet recording apparatus according to claim 1, wherein

the preservation solution further comprises an acetylene glycol-based surfactant represented by the following formula:

wherein R1, R2, R3 and R4 are independently an alkyl group and the sum of m and n is 0 to 50.

- The ink-jet recording apparatus according to claim 1, wherein

the preservation solution does not contain any coloring agent.

- The ink-jet recording apparatus according to claim 1, wherein the base polymer consists essentially of a butyl rubber polymer.

- The ink-jet recording apparatus according to claim 1, wherein the rubber member used in the ink passage is a cap, wiper, seal packing, or a tube.
